HIRAM PERCY MAXIM, OF HARTFORD, CONNECTICUT, ASSIGNOR TO MAXIM SILENCER COMPANY, OF HARTFORD, CONNECTICUT, A CORPORATION OF CONNECTICUT.

SILENCER.

Application filed October 29, 1924. Serial No. 746,614.

This invention relates to silencers such as are used for silencing the exhaust noises of internal combustion engines and is especially designed to be used in silencing the exhaust noises of small engines of the outboard type having one or two cylinders.

One object of the invention is to provide a compact and light silencer for an engine of the above type which effectually silences the exhaust with a minimum of back pressure thereby rendering a cut out necessary.

Another object is to provide a silencer wherein the various improved features of construction and design contribute to the efficiency and durability of same and to the production of an efficient and reliable silencer at low manufacturing cost.

To the accomplishment of the above and further objects as will hereinafter appear, the invention consists in the features of construction and in the combination and arrangement of parts which will be first described and then particularly pointed out in the claims.

The invention will be explained in connection with the accompanying drawings in which:

Fig. 1 is a side view partly in section of a silencer designed for a two cylinder engine;

Fig. 2 is a vertical section taken on the line 2—2 of Fig. 1;

Fig. 3 is a side view of the outer shell of the silencer;

Fig. 4 is a broken side view of one of the inner shells; and

Fig. 5 is a longitudinal sectionalized view of a modification adapted for use with a single cylinder engine.

Referring to the drawings,—the improved form of silencer shown in Fig. 1 is designed for use a two cylinder out board motor of the usual type having its cylinders diametrically opposed and with simultaneous exhaust. This form consists of the outer cylindrical shell 1, preferably constructed of sheet metal seamed longitudinally at 2, as shown in Fig. 3. The ends of the shell are closed by removable annular plates 3, 3, each of which is provided with a circumferential flange 4, fitting tightly over the ends of the shell 1. Each end plate 3 also has a hollow axial protuberance 5 to provide a small axial chamber 6 in the inner wall thereof opening into each end of the shell

1 and integral with said end plate is an arm 8 adapted for use as a supporting arm in attaching said silencer to the engine (not shown). The arm 8 may also be hollow to provide a passageway 7 leading from the 60 exhaust port of the engine to the inlet side of said silencer.

Within the shell 1 is a silencing device 9 preferably constructed of two annular scroll members or units 10, 10, each formed 65 to provide a continuous winding or spiral channel 11, 11, united as one passageway leading from the axis to the periphery thereof. To this end, each of the members 10, 10 comprises a flat annular plate 12 with a 70 central aperture 15 and what is in effect a spiral rib 13 which projects at right angles to the plate 12 and which forms between its convolutions the winding or spiral channel 11 for the exhaust gases. In 75 practice, it is preferred to make the ribs 13 not as true spirals but concentric circular segments for somewhat more than three quarters of a circle and to connect the corresponding ends of each concentric portion 80 with the opposed ends of the ribs of the next smaller diameter, as clearly shown in Fig. 2. The outer convolution or concentric segmental rib is at the periphery of the plate, and is adapted to be slightly smaller 85 in diameter than the inside diameter of the shell 1. These two scroll members 10, 10 are identical in construction and are assembled within the shell 1 with the free edges of their respective spiral ribs 13 in 90 abutting relation during the entire length thereof, and with these edges meeting at a point approximately midway between the ends of the shell 1. Due to the slightly 95 smaller diameter of the outer convolution of these members, they are easily assembled within the shell, but fit snugly therewith and are removable for cleaning. Other forms of removable silencing units composed 100 of annular plates with axially projecting ribs to provide a tortuous passageway extending radially outward from the central opening may also be used in a similar manner to that shown.

It will be seen that by thus assembling the 105 two scroll members 10, 10 within the shell an expansion chamber 14 is formed at each end thereof, and these chambers 14 are connected by an axial passageway formed by the centrally located apertures 15 in the 110

members. It is also apparent that the two spiral channels 11, 11 form a single continuous closed spiral passageway which leads from the axis of the shell to the periphery thereof; the inner and outer ends of the spiral ribs forming respectively the inlet 16 and the outlet 17 to said passageways. That portion of the shell 1 at the outer end of the spiral passageway which registers therewith is cut away forming a lateral port 18 in the shell 1, whereby the exhaust gases are discharged into the atmosphere.

In order to strengthen the assembly of the various parts of the device and to assist in holding the scroll members 10, 10 in place, I provide two inner cylindrical shells 19, 19 which are slightly smaller in diameter than the outer shell 1, and are preferably constructed of sheet metal seamed at 20, as shown in Fig. 4. These inner shells 19, 19 fit closely within the outer shell 1 and extend from opposite ends of the scroll members 10, 10 to the inner walls of the end plates 3, 3. A tie-bolt 21, provided at either end with nuts 22, 22, extends through shell 1 and the end plates 3, 3, thereby firmly holding the parts together, as clearly shown in Fig. 1.

In use with an engine of the type having two opposed cylinders with simultaneous exhaust, the exhaust gases and sound waves from each cylinder pass into the expansion chambers 14, 14 at either end of the silencer simultaneously and then into the axial passageway 15 connecting the two chambers 14, 14 where the gases and sound waves of one cylinder oppose those of the other and are thereby constrained to pass through the spiral passageway 11 and out through the lateral port 18 into the atmosphere. During the passage of the gases and sound waves in this manner, the sound waves are largely trapped by repeated reflections against the walls of the chambers 14 and of the spiral passageway 11 whereby the remnants of sound waves finally emerging from the lateral port 18 are substantially noiseless. The gases on the other hand flow easily in a spiral course toward the discharge port 18 and are not substantially retarded in their flow, thereby avoiding excessive back pressure on the engine.

In Fig. 5, I have shown the adaptation to a single cylinder engine of a silencer of the above type, and will now describe briefly the construction of the same.

Referring to Fig. 5, this form consists of the outer cylindrical shell 1' having its ends closed by the end plates 3' and 3''. The end plate 3' has a hollow protuberance 5' to provide a small axial chamber 6' in the inner wall thereof opening into one end of the shell 1, but the other end plate 3'' is preferably constructed without any axial

chamber. Integral with the end plate 3' is the hollow supporting arm 8' having the passageway 7' therein for receiving the exhaust of the single cylinder engine. The other end plate 3'' is also provided with its integral supporting arm 8'', but is without the hollow passageways 7' or chamber 5'.

Within the shell 1' is a single scroll member 10' constructed in all respects similar to one of the members 10 of the first described type of silencer. This member 10' is assembled within the shell 1' with the free edges of its spiral rib in abutting relation with the inner wall of the end plate 3'' thus providing an expansion chamber 14' at inlet 80 end of the silencer. There is also provided an inner cylindrical shell 19' for the same purposes and of the same construction as the shell 19, 19 of the first described type of silencer. A tie-bolt 21' provided with nuts 22', 22' extends through the shell and the end plates 3', 3'' and holds the parts firmly together.

In the use of this type of silencer with a single cylinder engine, the gases act similar 90 as in the first described type and are exhausted through the lateral port 18' formed in the shell 1'.

It will be thus observed that an improved silencer for a two cylinder engine having 95 simultaneous impulses or for a single cylinder engine has been constructed in which the various parts are compactly arranged and firmly secured together by a single bolt. The improved silencer may be of very light 100 construction, is easily and quickly assembled and provides an extremely efficient and durable muffler for engines of the above types. A further advantage lies in the fact that the parts of the silencer are removable 105 and may be easily disassembled for cleaning.

What I claim is:

1. A silencer for internal combustion engines and the like comprising, a cylindrical shell, end members for closing the ends 110 of said shell, each of said end members having an inlet for the exhaust gases, a pair of scroll members fitting within said shell and each comprising a centrally apertured base with a spiral rib projecting therefrom, said scroll members being assembled within said shell in opposed relation with the free edges of their respective ribs abutting to provide a closed spiral passageway extending from the axis of said shell to the periphery thereof, means for spacing said abutting scroll members from each end of said shell to provide an expansion chamber at each side of 115 said annular member, and a lateral exhaust port in the side wall of said shell intermediate the ends thereof.

2. A silencer for internal combustion engines and the like comprising, an outer cylindrical shell, end members for closing the 120 ends of said shell, each of said end members

- having an inlet for the exhaust gases, a pair of scroll members fitting within said shell and each comprising a centrally apertured base with a spiral rib projecting therefrom, 5 said scroll members being assembled within said shell in opposed relation with the free edges of their respective ribs abutting to provide a closed spiral passageway extending from the axis of said shell to the periphery thereof, inner spacing shells between said scroll members and the end members to provide an expansion chamber at each side of said annular members, a lateral exhaust port in the side wall of said outer shell intermediate the ends thereof and a single tie bolt for holding the various parts in assembled position.
3. A silencer for an internal combustion engine and the like, comprising a cylindrical shell, end members for closing the ends of said shell, one of said end members having an inlet for the exhaust gases, a scroll member fitting within said shell comprising a centrally apertured base with a spiral rib 20 projecting therefrom to form a closed spiral passageway from the axis to the periphery of said shell, said scroll member being spaced from the inlet end member to provide an expansion chamber for said gases, and a lateral outlet for said gases in the side of said cylindrical shell.
4. A silencer for an internal combustion engine and the like, comprising a cylindrical shell, end members for closing the ends of said shell, one of said end members having an inlet for the exhaust gases, a scroll member fitting within said shell comprising a centrally apertured base with a spiral rib projecting therefrom to form a closed spiral passageway from the axis to the periphery 25 of said shell, a lateral opening for the said gases in the side of said cylindrical shell, means for spacing the base of said scroll member from the inlet end member to provide an expansion chamber for the exhaust 30 gases and a single tie bolt for holding said parts in assembled relation.

In testimony whereof I have affixed my signature.

HIRAM PERCY MAXIM.

Certificate of Correction.

It is hereby certified that in Letters Patent No. 1,601,136, granted September 28, 1926, upon the application of Hiram Percy Maxim, of Hartford, Connecticut, for an improvement in "Silencers," errors appear in the printed specification requiring correction as follows: Page 2, line 124, claim 1, and page 3, line 13, claim 2, for the word "annular" read *scroll*; page 3, line 30, claim 3, after the word "outlet" insert the word *opening*; and that the said Letters Patent should be read with these corrections therein that the same may conform to the record of the case in the Patent Office.

Signed and sealed this 19th day of October, A. D. 1926.

[SEAL.]

WM. A. KINNAN,
Acting Commissioner of Patents.
